DISPLAY STAND FOR FINGER RINGS OR THE LIKE

Everett Petrosinelli, Cranston, R.I., assignor to Richton International Corporation

Filed Mar. 17, 1975, Ser. No. 559,375

Term of patent 14 years

Int. Cl. D20—02

U.S. Cl. D6—141

FIG. 1

FIG. 2

FIG. 4

FIG. 1 is an elevational view of a display stand for finger rings or the like showing my new design, looking in the direction of arrow 1 in FIG. 4;

FIG. 2 is an elevational view thereof looking in the direction of arrow 2 in FIG. 4;

FIG. 3 is a bottom plan view thereof; and

FIG. 4 is a top plan view thereof.

I claim:

The ornamental design for a display stand for finger rings or the like, substantially as shown.
